UNITED STATES PATENT OFFICE.

BEN M. STONE, OF CHICAGO, ILLINOIS.

LOCK.

1,328,106.

Specification of Letters Patent. Patented Jan. 13, 1920.

Application filed June 8, 1918. Serial No. 238,875.

To all whom it may concern:

Be it known that I, BEN M. STONE, a citizen of the United States, and a resident of Chicago, in the county of Cook and State 5 of Illinois, have invented certain new and useful Improvements in Locks; and I do hereby declare that the following is a full, clear, and exact description thereof, reference being had to the accompanying drawings, and to the letters of reference marked thereon, which form a part of this specification. 10

This invention relates to new and useful improvements in locks for traveling cases, 15 bags, trunks or similar articles, and consists in the matters and things illustrated and hereinafter more fully described and claimed.

In the drawings:

20 Figure 1 illustrates in a front elevation, a traveling suit case or bag, embodying my invention.

Fig. 2 is an enlarged, vertical, sectional view through the lock and the supporting 25 members for the several parts thereof.

Fig. 3 is a detached plan view of a portion of one of the supporting parts to which my lock is attached.

Fig. 4 is a perspective view of the keeper 30 member of one of the locks.

Fig. 5 is a perspective view of that portion of the lock adapted to be engaged by the keeper member illustrated in Fig. 4.

Fig. 6 is a perspective view of a plate 35 and the hasp member of the second lock.

Fig. 7 is a perspective view of a lock member adapted to be engaged by the hasp member illustrated in Fig. 6.

In that embodiment of my invention 40 shown in the drawings, I have chosen to illustrate the use of my improved lock in connection with a traveler's suit case or bag, represented as a whole by the letter A. Such a bag has a lower compartment B, an 45 upper or top compartment C and an intermediate partition member D.

The lower compartment B is provided with a front supporting member or wall 1; the upper compartment by a supporting 50 member or wall 2; and the intermediate partition is provided with a supporting member or wall 3. Upon the front face of the support 1 is an escutcheon plate 4 secured thereto by screws or rivets passing 55 through suitable apertures 5 in said plate. Said plate 4 is also provided with a suitably

shaped hasp slot or aperture 6 and with a movable or sliding knob 7 of a conventional lock mechanism. A key-hole slot 8 in said knob 7 affords access to the lock mechanism 60 of the bolt 9. 10 is a slotted tongue on the hasp 11, said tongue being adapted to enter the slot 6 and to be engaged by the bolt 9.

12 is a second plate adapted to be secured to the front face of the supporting member 65 or wall 3 by means of bolts or rivets passing through the apertures 13 of said plate 12. 14 is a lock casing adapted to be suitably secured to the support 3 by any convenient means. Said lock frame 14 may also be 70 secured to that part of the support 3 constituting the supporting partition D, by means of screws or rivets, passing through apertures in the laterally extending flanges 15 of said lock casing 14, or otherwise. 75

Projecting outwardly from the face of the lock casing 14 is a tubular sleeve or extension member 16, adapted to pass through a suitable aperture 17 in the escutcheon plate 12. A lock releasing spring 80 pressed bolt member 18 extends longitudinally through the sleeve 16. Upon its inner end, said bolt 18 is provided with a spring 19, one end of which presses against the interior rear wall of the lock casing 14 85 and tends to normally press the bolt member 18 outwardly into position shown in Figs. 2, 3 and 5. The releasing member 18 is provided with a longitudinally extending key-hole slot or aperture 20 affording means of 90 access for a suitable key to release the lock or bolt member 18, and permit of its longitudinal movement.

21, 21 are slotted tongue members on a keeper 22 which tongue members 21 are 95 adapted to enter slotted apertures 23 in the lock casing 14, there to be engaged by hooked ends 24 of the bolt member 18.

Upon the escutcheon plate 12, I provide an extension leaf or tongue 25, and on the 100 hasp 11, I also provide an extension tongue 26. The proximate edges of the tongues 25 and 26 are formed to interlock in a familiar manner and to extend about a transversely arranged pintle or hinge pin 27. 28 is a 105 coiled spring surrounding the hinge pin 27 and adapted to exert outward pressure upon the tongue 26 and hasp 11. It will be understood that when the hasp 11 is released from engagement with the bolt 9, the 110 hasp 11 will normally be moved under the influence of the spring 28, outwardly away

from the support 1 and escutcheon plate 4, the hasp 11 and its tongue 26 turning about the pintle or hinge pin 27 in a familiar manner.

5 When my improved lock is applied to the supporting members 1, 2 and 3, which constitute part of a traveler's suit case, for example, it will be noticed that the member 22 and slotted tongues 21, 21, are not visible 10 from the exterior and that the suit case as a whole presents a neat appearance.

It will be manifest from the foregoing that the three supporting members, 1, 2 and 3, may be locked together or the members 1 15 and 3, or the members 2 and 3, may be locked together. By operating a key in the keyhole 20 and pressing the bolt member 18 inwardly the lock ends 24 are released from engagement with the slotted tongue 21, the 20 supporting member 2 may be raised quite independently of the supporting member 3, and the latter remaining securely locked to the supporting member 1. Similarly the three members 1, 2 and 3 being locked together, 25 a key may be inserted and operated in the keyhole 8 and the knob 7 moved to release the bolt 9 from the slotted tongue 10, whereupon the spring actuated hasp 11 will become disengaged. The supporting 30 member 1 may then be moved downwardly away from the supporting member 3 or the locked-together, supporting members 2 and 3 may be simultaneously raised away from the supporting member 1.

35 This new and improved lock is adaptable to many forms of travelers' suit cases, bags and trunks, and it is also adapted for use with other articles of merchandise, such for example, as furniture, jewelry cases and the 40 like. I therefore do not desire to have my invention limited to any particular use nor to have the invention restricted except as and in the manner set forth in the subjoined claims.

45 I claim as my invention:

1. A key-hole lock and its support, a plate therefor, a hinged spring pressed hasp depending from said plate, a second key-hole lock and a support therefor, said second lock 50 being adapted for operative engagement with the spring pressed hasp, and a keeper member for engagement with said first mentioned lock.

55 2. A support, a plate on the face of said support, a key-hole lock attached to said support, an integral leaf on and projecting at right angles to the longitudinal axis of said plate and provided with a hinge or pintle pin, the axis of the pin being parallel 60 with the longitudinal axis of the plate, a hasp member hingedly secured to said leaf by said pin, a second key-hole lock, a support therefor, said lock being adapted for operative engagement with said hasp member, a 65 keeper member adapted for operative en-

gagement with the first mentioned lock, and a support for said keeper member.

3. In a device of the character described, two key-hole lock mechanisms, a plate associated with one of said lock mechanisms, a 70 hasp member hingedly secured to said plate and adapted for operative engagement with the other lock mechanism.

4. In a device of the character described, a lock mechanism provided with a laterally 75 extending tubular keyhole member, a keeper member, a plate associated with said lock and provided with an aperture for said tubular keyhole member and with a leaf member depending from one of its longitudinal 80 margins, a second lock mechanism, a hasp member therefor and pivotal connections between said hasp member and the leaf member including a coiled spring adapted to exert outward pressure upon the hasp member. 85

5. A device of the character described comprising two support members, the supporting surfaces of which are in the same plane, a lock mechanism secured to the face of one support, a second lock mechanism secured to the other support, a plate upon the latter support, a hasp member hingedly secured to said plate and adapted for operative engagement with the first lock mechanism, a third support and a keeper thereon 90 adapted for operative engagement with the second lock mechanism, the plate being also in operative relation to the second lock mechanism.

6. A support and a keeper secured thereto, a second support, a plate on the face of the latter, a lock mechanism also on said second support and in alinement with said keeper, a movable member in said lock mechanism having one end projecting beyond the 100 face of said plate, a third support, a lock mechanism on the face thereof and a hasp member hingedly secured to said plate and adapted for operative engagement with the 105 last mentioned lock mechanism. 110

7. A support and a keeper secured thereto, a second support, a plate on the face of the latter, a lock mechanism also on said second support and in alinement with said keeper, a movable member in said lock mechanism having one end projecting beyond the 115 face of said plate, a third support, a lock mechanism on the face thereof and a hasp member hingedly secured to said plate and adapted for operative engagement with the last mentioned lock mechanism, the outer surfaces of said three supports being substantially in alinement in the same plane. 120

8. A lock mechanism and a support therefor, a plate and a support therefor, a hasp member hingedly secured to said plate, and adapted for operative engagement with said lock mechanism, a second lock mechanism secured to the plate support, in a plane other than that of the plate, a part of said lock 125 130

mechanism being in operative engagement with said plate, a third support in substantial alinement in the plane of the other two supports, and a keeper member on the third support positioned in a plane other than that of the first mentioned lock, and of said plate, and adapted for operative engagement with said second lock mechanism.

In testimony that I claim the foregoing as my invention I affix my signature in the presence of two witnesses, this 6th day of June, A. D. 1918.

BEN M. STONE.
